CLAIM

The ornamental design for a computer housing removal tool, as shown.

DESCRIPTION

FIG. 1 is a perspective view of the computer housing removal tool showing my new design;

FIG. 2 is a side elevational view thereof;

FIG. 3 is a bottom plan view thereof;

FIG. 4 is a top plan view thereof;

FIG. 5 is an end elevational view thereof; and

FIG. 6 is the other end elevational view thereof.
